UNITED STATES PATENT OFFICE.

MACK M. SWAIN, OF LOS ANGELES, CALIFORNIA.

PEDAL COVER.

Application filed July 6, 1926. Serial No. 120,828.

This invention relates to improvements in covers for accelerator pedals and the like.

The primary object of this invention is the provision of an improved cover for accelerator pedals of any approved type, but preferably for the type of accelerator pedal set forth in my copending application, Serial No. 94,495, filed March 13, 1926, and characterized by novel constructional features which will permit of its facile attachment and detachment with respect to the accelerator pedal, and so that adults and children having various lengthened shoes may accommodate their feet to the pedal cover.

Other objects and advantages of the invention will be apparent during the course of the following detailed description.

In the accompanying drawing, forming a part of this specification, and wherein similar reference characters designate corresponding parts throughout the several views,

Figure 1 is a longitudinal sectional view taken thru the improved accelerator pedal cover showing the application of the same upon an accelerator pedal.

Figure 2 is a bottom plan view of the improved yieldable pad or cover showing the same detachably affixed to the top plate of the accelerator construction of the type set forth in my co-pending application above referred to.

Figure 3 is a longitudinal sectional view taken through the cover showing the details as illustrated in Figure 1, but with the flexible foot contact pad or cover raised at the forward end thereof to show the ease of attachment and detachment of the cover or pad with respect to the foot plate of the pedal construction.

Figure 4 is a transverse sectional view taken substantially on the line 4-4 of Figure 5, thru the resilient cover or pad.

Figure 5 is a perspective view of the top side of the improved cover or pad.

Figure 6 is a perspective view of the improved cover or pad from the bottom side or surface thereof.

In the drawing, wherein for the purpose of illustration is shown only a preferred embodiment of the invention, the letter A may generally designate the improved pad or cover, which is adapted to be detachably assembled upon the foot rest plate B of any approved type of accelerator pedal.

As to the foot plate B, the same in the instance illustrated is preferably of the rigid

metal type, elongated in character, and of preferably uniform width throughout the major length thereof, but preferably rounded at the rear edge 10 thereof as illustrated in dotted lines in Figure 2 of the drawing, and at the front end thereof the same is tapered by converging side edges 11 and 12 to a blunt straight edge 13 arranged preferably at right angles to the longitudinal axis of the body 14 of the plate. On the lower surface thereof the plate B is preferably provided with apertured lugs 16 to secure the attachment of the same upon other operating details of the accelerator pedal, not forming a part of this invention, but described in my co-pending application above referred to. The plate B from end to end is of uniform thickness, with the exception of the lugs 16.

Referring to the pad, mat, or cover A, the same is adapted for detachable assemblage upon the plate B, and is formed of some flexible or resilient material, such as rubber. It is moulded to form, and all parts thereof are preferably integral but may be made separable if found practical. In the preferred construction thereof the same includes a relatively thick elongated body portion 20, which is in substantially the form of a sole and heel of a foot of a person, and at the lower surface thereof the same is provided with the thickened side marginal portions 21 and 22, and the rear thickened portion 23 about the rear margin. The thickened portions 21, 22 and 23 are contiguous and extend below the lower surface 24 of the body 20 of the foot pad or cover, and the said thickened portions 21 and 22 terminate short of the front portion of the pad body 20, at a distance approximately one-third the total length of the cover A. Along these margin thickened portions 21, 22 and 23 are provided the reduced flanges 27, 28 and 29, which are respectively integrally connected with the thickened portions 21, 22 and 23, and face inwardly over the surface 24 of the body 20 in a spaced relation therewith, to provide a substantially U-shaped groove 30 in which the marginal portions of the foot plate B may be received. These overhanging flanges 27 and 28, it may be noted, are preferably of uniform overhang along the cover sides, but at the base or rear end of the pad A the flange 29 overhangs for a greater distance so that the rear end of the plate 14 of the accelerator pedal extends into the socket provided by this overhang flange 29 a greater distance than the side margins of the plate 14 extends into

the channels or grooves formed by the overhanging flanges 27 and 28, as can readily be seen from the dotted lines in Figure 2 of the drawing. The flanges 27 and 28 and thickened portions 21 and 22 respectively thereof, as above mentioned, extend to a point short of the toe end of the foot pedal pad or cover A, approximately in the vicinity of the forward pair of lugs 16, and thus about one-third of 10 the length of the cover A is not provided with any flanges or guide grooves for receiving the foot plate 14, so that the toe portion 35 of the resilient or flexible mat or cover A may be lifted upwardly from the front end of the 15 plate 14, as is illustrated in Figure 3 of the drawings in full lines. The retaining lug 37, preferably solid, is formed on the bottom surface of the toe portion 35 of the mat or cover A, and adapted for abutment against the 20 straight edge 13 of the front of the plate 14, to prevent the sliding of the mat A rearwardly, when the plate B is received in the grooves provided by the overhanging flanges 27, 28 and 29. The U-shaped grooves provided by 25 these overhanging flanges in lieu of the formation above described, may be termed a "pocket", since it is entirely practical to provide a pocket in the rear end of the cover or mat A into which the rear end of a foot plate 30 may be slipped, so that the front end of the cover is unobstructed by the pocket and the foot plate may extend therefrom to permit 35 the lifting of the front end of the cover plate much in the same manner as illustrated in the drawing, to enable the facile attachment and detachment of the rubber or flexible cover plate with respect to the rigid plate 14.

It should be noted that the block or lug 37 is preferably solid and is provided with a 40 rearwardly facing straight edge 40, which is not obstructed by any overhanging pockets and which receives the straight edge in a snug abutment therein, to properly retain the pad or cover A in place with the marginal portions along the side and rear of the plate 14 assembled in the U-shaped grooves provided by the overhanging flanges 27, 28 and 29, as is well illustrated in the drawing. It is to be noted that, from the locking lug 37 for a 45 short distance rearwardly towards the rear of the cover A, the body 20 is not provided with the retaining flanges and this is the feature which enables the upward lift of the toe portion 35 to permit the detachment or proper attachment of the cover A upon the plate B, as is quite obvious.

The top surface of the body 20 is formed in a novel manner. It includes a heel portion 45 adapted to receive the heel of the 50 shoes of persons having large feet, and which heel portion 45 may be serrated or cross-grained in any approved relation. At the front of the heel portion 45 a transverse retaining strip or rib 46 is provided, transversely across the body 20, and immediately

forward of this strip or rib 46 is formed a heel socket 47, adapted to receive the heels of small sized shoes, or the heels of children or persons having small feet. Forwardly of the heel socket 47, the upper surface of the pad 70 or body 20 of the cover A may be suitably formed in the shape of a sole and may be serrated at 48, if desired to prevent the slipping of the foot thereon. The forward facing surface of the transverse rib 46 may be arcuated at 49 to facilitate the proper sliding of the heel of the person with small feet there-over.

From the foregoing description of this invention it is apparent that a novel type of 80 accelerator pedal cover or mat has been provided, which may be moulded in an integral construction to enable the facile attachment or detachment with respect to the accelerator pedal, and which is so designed as to receive 85 the feet of persons having long or short feet, in an entirely stable and efficient relation, especially when taking into consideration the construction of the accelerator pedal set forth in my co-pending application above referred to.

Various changes in the shape, size, and arrangement of parts may be made to the form of invention herein shown and described, without departing from the spirit of the same 95 or the scope of the claims.

I claim:

1. As an article of manufacture a resilient foot rest pad for accelerator units substantially conforming to the shape of the bottom 100 of a shoe and the top surface including a heel portion forwardly of which is formed a transverse upwardly projecting rib, the member forwardly of said rib having a heel receiving socket therein at the opposite side of 105 the rib from said heel portion above mentioned.

2. As an article of manufacture a moulded rubber cover pad for accelerator pedals comprising an elongated body including a front toe portion, a rear heel portion and an intermediate portion, the intermediate portion and heel portion on the lower surface of the body being provided with overhanging retaining flanges providing a substantially U- 115 shaped groove and the toe portion on the lower surface thereof being unobstructed by such flanges but having a depending button lug extending downwardly therefrom along the longitudinal axis of the body, the upper surface of the body at the juncture of the rear heel portion and intermediate portion of the body having an upwardly extending transverse retaining rib and the intermediate portion inwardly of the top surface thereof 120 forwardly of said rib having a depending heel receiving socket therein.

3. As an article of manufacture a flexible pedal cover adapted to be applied to accelerator pedals and the like comprising a flex- 130

ible body portion having the lower surface thereof provided with a peripheral flange projecting beyond the plane of said lower surface for a portion only of the periphery, 5 said flange having a transverse flange thereon overhanging in spaced relation the lower surface of the body to provide a pocket, one end of the body having the lower surface entirely free of the flanges above mentioned,

and said lower surface at said last mentioned end of the body having a small narrow dependent lock lug thereon adapted to engage an edge of a pedal plate in a non-overhanging relation whereby the said end of the body may be lifted and flexed without gripping 15 engagement on the pedal plate, to permit the plate to slide from the pocket of the body.

MACK M. SWAIN.
